ATTYS.

UNITED STATES PATENT OFFICE.

WALTER C. KEMPTON, OF SAN FRANCISCO, CALIFORNIA.

HEEL.

937,535.

Specification of Letters Patent. Patented Oct. 19, 1909.

Application filed July 8, 1908. Serial No. 422,560.

To all whom it may concern:

Be it known that I, WALTER C. KEMPTON, a citizen of the United States, residing at San Francisco, in the county of San Francisco, State of California, have invented certain new and useful Improvements in Heels, of which the following is a specification.

My invention relates to new and useful improvements in rubber heels and bottoms for boots and shoes and has for its objects to prevent slipping by their engagement with the surfaces upon which the heels rest, and to reinforce the wearing surfaces or parts of rubber heels so as to increase their durability and usefulness.

I aim to provide a form of reinforced and non-slipable rubber heel which will be serviceable and can be manufactured at low cost.

The accompanying drawings, which form a part of this specification, illustrate forms of reinforced rubber heels constructed in accordance with my invention.

In the said drawings: Figure 1 is a plan view of a heel with a portion of the rubber broken away showing a coil in place. Fig. 2 is an elevation of the same. Fig. 3 is a broken plan view showing an arched wire within the coil. Fig. 4 is a broken elevation view showing a coil elliptical in shape; and Fig. 5 is a plan view of a heel with a portion of the rubber broken away showing a coil circular in form with a segment of its circumference parallel with the segment of the circle formed by the heel.

In the invention, wire, preferably of steel, is coiled and inserted longitudinally in the rubber within the periphery of the heel parallel with the whole or a part of its segment, as may be desired, and with its one surface in substantially the same plane as the lowermost surface of the heel. It is preferable that the wire coil have equal resiliency with the rubber so that none of the advantages of the rubber heel be lost. I prefer using a coil elliptical in shape, as shown in Fig. 4, as a greater portion of metallic surface can be placed closer to the bottom or outer surface at the lower plane of the heel, adding to the support of the rubber and providing a greater wearing metal surface at the part of the heel where the wear is the greatest. This coil can be placed within the whole or a part of the periphery of the heel as desired.

In Fig. 3 is shown a metal strip, or wire, curved to conform with the periphery of the

heel placed within the coil wire. It is designed to hold the coil in place during the process of manufacture and to assist in retaining the coil in place should any part of the rubber be worn or broken away but I do not restrict myself to its use.

At Fig. 5 I show a wire coil forming a complete circle. This circle is of such diameter as to be less than the diameter of the segment of the circle formed by the curved portion of the heel and the coil so formed is so placed within the rubber that a segment of its circumference parallels that of the segment of the circle formed by the curve of the heel.

A plurality of perforated metal disks or washers are inserted in the rubber as shown in Figs. 1, 2 and 3 and in the rubber are perforations to register with the perforations in the disk through which the nails or screws can be inserted as a suitable means for attaching the heels to boots or shoes though any other well known device may be used.

Having described my invention what I claim as new and desire to secure by Letters Patent is:—

1. A rubber heel, a wire coil inserted longitudinally within the rubber within and close to the periphery of the heel, and parallel with the outer edge of said heel, the lower surface of said coil lying in substantially the same plane as the lowermost surface of the heel.

2. A rubber heel, a wire coil inserted longitudinally within the rubber within and close to the periphery of the heel, a portion of said coil being parallel with the rearmost curved edge of the heel, said coil having its lower surface in substantially the same plane as the lowermost surface of the heel.

3. A rubber heel, an elliptical wire coil inserted longitudinally within the rubber within and close to the periphery of the heel and parallel with the outer edge of said heel, said coil having its lower surface in substantially the same plane as the lowermost surface of the heel, and a metal core within the wire coil.

In testimony whereof I have affixed my signature in the presence of two witnesses this 25 day of June 1908.

WALTER C. KEMPTON.
